UNITED STATES PATENT OFFICE

MARTIN W. CLEMENT, OF HAVERFORD, PENNSYLVANIA

METHOD OF INSPECTING RAILROAD CARS AND APPARATUS THEREFOR

Application filed June 13, 1930. Serial No. 460,821.

This invention relates to a method of inspecting the underparts, i. e. the trucks, center sills, brake rigging, couplers and other attachments visible from beneath, of moving railroad cars, especially freight cars, and relates also to an inspection pit located beneath a section of track and so designed and equipped with a variety of appliances as to permit an observer therein to make a complete underneath examination of passing cars and to mark for subsequent identification such cars as are defective.

The principal object of the invention is to reduce train accidents by eliminating a common cause of such accidents, namely, defective condition of the running gear or of parts or attachments on the underframe of cars, which condition under present railroad practice is frequently not detected and is too often the immediate cause of serious accidents. In the ordinary ground inspection of cars in a yard many defects which represent latent dangers are not detected because they are not visible from the ground. With freight cars such defects commonly include cracked arch bars, bent or broken center sills, and loose wheels, defects which sometimes can only be discovered by a thorough examination of the cars from beneath. My invention provides the facilities for conducting a careful inspection of the underparts of cars so that such cars as are in a dangerous or defective condition may be removed from service and repaired.

A further object of the invention is to provide an inspection pit so constructed that it can be readily installed and removed, or changed from place to place without difficulty, and so equipped that a single observer, adequately protected against injury and having a view lengthwise of the track and in both directions, can selectively mark defective cars and signal to a remote station whenever a car is so marked.

Still other objects of the invention will be apparent from the following detailed description of an example of the method of conducting an inspection of cars according to this invention and of an inspection pit designed for this purpose, the pit being illus-

trated in the accompanying drawings, of which:

Fig. I represents a plan view of two freight yards connected by a single track in which the inspection pit of this invention is located.

Fig. II represents a side elevation of the same showing the grade of the connecting track.

Fig. III represents an enlarged cross-section of the inspection pit and tunnel leading thereto, taken as indicated by the lines III—III of Fig. I.

Fig. IV represents an enlarged cross-section of the inspection pit taken as indicated by the lines IV—IV of Fig. III.

Fig. V represents a plan view of the inspection pit, its appurtenances, and the overlying section of track.

Fig. VI represents a longitudinal section of the same showing an observer in the pit inspecting passing freight cars.

Fig. VII represents a cross-section of the same taken as indicated by the lines VII—VII of Fig. VI.

Fig. VIII represents a longitudinal section similar to Fig. VI, but enlarged and showing in detail various appliances located in the inspection pit.

Fig. IX represents a cross-section of the same, taken as indicated by the lines IX—IX of Fig. VIII.

Fig. X is a detailed sectional view of a three-way valve controlling the delivery of a spray marking defective cars.

Fig. XI is a similar view showing the same valve with its handle turned to a different position; and

Fig. XII is a similar view showing the same valve with its handle turned to a third position.

Referring to Figs. I and II, there is diagrammatically represented a portion of a receiving yard comprehensively designated by the numeral 1, a portion of a classification yard similarly designated by the numeral 2 and a connecting track 3 with an inspection pit located at 4. Beyond the inspection pit 4 there is shown a down grade 5 leading to the classification yard 2.

As shown in Fig. II, the pit 4 is located

within an embankment and is accessible from both sides of the embankment through a tunnel constructed of a number of sections 6 of concrete pipe of substantially cylindrical form but flattened to provide a floor. The pit itself is substantially box-shaped and comprises a concrete floor 7, front and rear concrete walls 8 integral with the floor 7, and concrete arches 10 at the sides upon which 5 the rails 9 of the track 3 are supported. The arches 10 are made to conform with the interior dimensions of the concrete pipe sections 6. It will be apparent that the concrete pipe sections 6 used for the tunnel and the various 10 sections of the pit itself comprise concrete units which can be bodily installed, removed, and changed from place to place with a minimum of labor, the structure nevertheless being of ample strength and rigidity to support 15 with a considerable margin of safety the overlying track.

The station for the observer comprises a revolvable seat 11 having, as clearly illustrated in Fig. VIII, a screw threaded shaft 12 20 engaging in a similarly threaded support 13, so that the chair may be raised or lowered and revolved from side to side. The support 13 includes a foot rail 49 which enables the observer to reverse the position of the seat 11 by 25 pushing with his feet, his hands being occupied in performing other services. Immediately above the observer's station and bridging the side walls 8 of the pit, there is a protective covering in the form of a metal casing 30 35 14. The casing 14 comprises a roof 15 extending across the track 3 at substantially the level of the top of the rails 9 and front and rear inclined portions 16 having openings 17 therein permitting an unobstructed view 40 along the track in both directions. Slidable windows 18 are provided at the openings 17 so that the pit may be completely covered when not in use. Joining the inclined portions 16 of the casing 14 with the side walls 8 45 45 of the pit are horizontal portions 19 upon which a number of searchlights 20, 21 are mounted.

Two pairs of searchlights 20 are mounted, one pair at the front and one pair at the rear 50 of the casing 14, on brackets 22 and are so directed as to cast their beams from the sides of the track 3 toward the center and at such an angle as to illuminate the underparts of a car just as it approaches or leaves the inspection pit. Two additional searchlights 21 are mounted on the casing 14, one in front and one at the rear, centrally between the rails, these searchlights being adapted to be swivelled about the joints 23 by means of the hinged extensions 24, which pass through the casing 14, so as to be readily accessible to the observer. By means of the searchlights 21 the observer may focus a beam of light upon any particular part of a passing car which 60 65 65 requires special attention. The searchlights

20, 21 herein described have been found to provide ample illumination for inspecting cars at night and enable the continuous use of the pit, day and night, for inspecting all cars passing thereover.

The apparatus for marking defective cars for subsequent identification comprises generally a whitewash service tank 25, spray jets 26 and various appliances and fittings for controlling the spray. It will be obvious that other forms of coloring material may be used instead of whitewash, and that the system for spraying the coloring medium as herein-after described represents merely one convenient method of marking or identifying 70 75 80 defective cars.

As shown in Fig. V, air from a yard air-supply is admitted through a supply pipe 27, a stop valve 28 and gage 29 to two branches of a pipe 30. At the ends of the pipe 30 85 there are two three-way valves 31, 32 having pipe connections 33, 34 to the service tank, as well as pipe connections 35, 36 to the spray nozzles 26.

In Figs. X, XI, and XII, one three-way valve 31 is shown in each of the positions which it may assume, the normal position being that shown in Fig. X in which the air supply from pipe 30 is cut off and the tank 25 is in communication with the pipe 35 leading to a spray nozzle 26. When the valve 31 is turned by means of its handle 37 to the position shown in Fig. XI, air from pipe 30 is admitted to the tank 25 to agitate the whitewash and to charge the pipe 30 with whitewash. When the valve 31 is turned to the position shown in Fig. XII, air from pipe 30 is discharged together with the whitewash in the line through pipe 35 and spray nozzle 26.

The three-way valve 32 is adapted to be operated in the same manner to control the spray of whitewash through pipe 36 and the spray nozzle 26 located at the opposite side of the track. The observer by operating either valve 31, 32 located adjacent the seat 11 may selectively operate either spray nozzle 26 to spray the truck of a passing car with whitewash on one side or the other.

By means of this selection the observer may, for example, mark cars on one side to indicate defects in a car requiring that the car be taken to the shop for repair, or may mark cars on the other side to indicate defects which can be repaired in the classification yard.

At the top of the whitewash tank 25 a vent 38 and an opening 39 which can be used as an inlet for charging the tank are provided, and at the bottom of the tank there is shown a drain plug 40.

In addition to the marking apparatus there is also provided within convenient reach of the observer a bell ringer 41 which is used as a signal to a remote station to warn an inspector at that station to be on the lookout for cars marked as defective. Obviously if the 125 130

pit observer, or an assistant to him in the pit, maintains a record of the defects noted, though it is impossible for him to ascertain the car numbers of the cars on which the defects exist, this record can be subsequently used for comparison with the records of repaired cars, and a thorough checking of the results of the inspection and the repairs made may be had.

10 Adjacent each spray jet 26 there is shown a lamp 42 used as a marker to indicate the presence at that point of the spray jet.

In conducting inspections of cars with the use of the apparatus herein described, trains 15 in the receiving yard 2 are successively pushed by an engine onto the track 3 to a point on the grade 5 beyond the inspection pit 4, at which point the engine is uncoupled and the train permitted to move by its own weight to a 20 predetermined location in the classification yard 2. The engine after uncoupling returns by a run-around track to push other trains in succession over the inspection pit. The trains are moved at a slow uniform speed, 25 preferably about two miles per hour, over the inspection pit. At this rate of speed it has been found possible for an alert observer to make a thorough examination of each passing car, turning in his seat 11 to obtain both a 30 front and rear view of each truck as it passes the inspection pit, and manipulating the searchlights with one hand and the control valves of the marking apparatus and the bell ringer with the other hand. When a defect 35 is noted the observer, according to the nature of the defect, operates one of the control valves 31, 32 to deliver a jet of whitewash on the truck of the car overhead and immediately thereafter operates the bell ringer to warn 40 the advance inspector to be on the watch for a marked car. In the classification yard, the defective cars are segregated into two groups apart from the remaining cars, and the group requiring shop repairs is ultimately removed 45 for such repairs.

By means of the method herein outlined and the design and facilities of the inspection pit as herein described, train accidents may be considerably reduced in number. While 50 I have described the invention in some detail and with reference to a specific embodiment of the apparatus used and a specific example of the preferred method of conducting the inspection, it will be apparent that various 55 departures may be had from the practice of the invention as described without departing from the spirit of the invention as defined in the appended claims. I have illustrated 60 an inspection pit constructed in accordance with my invention situated between the receiving yard and the classification yard of a railroad system; but it will be understood that a similar inspection pit may be usefully 65 employed at the entrance to the receiving

yard or in any other convenient place in a railroad.

Having thus described my invention, I claim:

1. A method of inspecting railroad cars or the like for defects in underparts which consists in moving a train of cars at a slow uniform speed over an inspection station, examining each car from beneath as it passes over the inspection station, and marking for identification such cars as are defective.

2. A method of inspecting railroad cars or the like for defects in underparts which consists in moving at a slow uniform speed a series of trains from one yard to another over a track having an inspection station therebeneath, examining each car from beneath as it passes over the inspection station, identifying such cars as are defective, and segregating the defective cars in the last-mentioned yard.

3. A method of inspecting railroad cars or the like for defects in underparts which consists in successively pushing at a slow uniform speed a series of trains from a receiving yard to a track having an inspection station therebeneath and having a downward incline beyond said inspection station, examining each car from beneath as it passes the inspection station, and allowing each train to move by its own weight from said incline to a track in a receiving yard therebeyond.

4. A method of inspecting railroad cars or the like for defects in underparts which consists in moving a car at a slow uniform speed over an inspection station, examining each car from underneath as it passes over the inspection station, marking for identification such cars as are defective, and signalling to a remote station each time a mark is applied.

5. An inspection pit underlying a section of railroad track including a station from which an observer may inspect the underparts of cars passing thereover, and means at said station for marking such cars as are defective.

6. An inspection pit underlying a section of railroad track, including a station from which an observer may inspect the underparts of cars passing thereover, and a protective covering above said station, said covering having openings therein permitting a view lengthwise of the track in both directions.

7. An inspection pit underlying a section of railroad track, including a protective covering having openings therein permitting a view lengthwise of the track in both directions, and a revolvable seat beneath said protective covering.

8. An inspection pit underlying a section of railroad track, including a protective covering having openings permitting a view lengthwise of the track and a searchlight mounted on said covering.

9. An inspection pit underlying a section of railroad track, including a station from which an observer may inspect the underparts of cars passing thereover, a protective covering above said station having an opening permitting a view from said station lengthwise of the track, a searchlight mounted on the outside of said covering, and means on the inside of said covering for swivelling said searchlight. 70
10. An inspection pit underlying a section of railroad track, including a protective covering having openings therein permitting a view lengthwise of the track in both directions, a revolvable seat beneath said covering, searchlights mounted on said covering and adapted to cast their beams in opposite directions, and means accessible from said revolvable seat for swivelling said searchlights. 75
11. An inspection pit underlying a section of railroad track, including a protected station from which an observer may inspect the underparts of cars passing thereover, means for applying an identifying mark to such cars as are defective while such cars are moving over the station, and means readily accessible to the observer for controlling the operation of said marking means. 80
12. An inspection pit underlying a section of railroad track, including a protected station from which an observer may inspect the underparts of cars passing thereover, means for controlling the application of an identifying mark to such cars as are defective, and means for signalling to a remote station each time a mark is applied, said controlling means and signalling means being readily accessible to the observer. 85
13. An inspection pit underlying a section of railroad track, including a protected station from which an observer may inspect the underparts of cars passing thereover, means for delivering a spray to mark defective cars while such cars are moving over the station, and a valve accessible to the observer for controlling the operation of said spray. 90
14. An inspection pit underlying a section of railroad track, including a station from which an observer may inspect the underparts of cars passing thereover, and means at said station whereby the observer may selectively mark cars while moving over said station to indicate different classes of defects. 95
15. In combination an inspection pit underlying a section of railroad track comprising a number of concrete sections forming a substantially box-shaped structure and a tunnel leading to said pit comprising sections of concrete pipe, said tunnel and pit concrete sections being bodily removable without demolition. 100
16. In combination a substantially box-shaped concrete inspection pit, including a floor, front and rear walls, and arches supporting the rails of an overlying section of track; and a tunnel leading to said pit comprising sections of concrete pipe abutting said rail supporting arches. 105
